H. LÜBECK.
PNEUMATIC SLEEPER FOR RAILROADS.
APPLICATION FILED JAN. 20, 1919.

Charles Parker

UNITED STATES PATENT OFFICE.

HILDING LÜBECK, OF HERSERUD, SWEDEN.

PNEUMATIC SLEEPER FOR RAILROADS.

1,358,764.

Specification of Letters Patent. Patented Nov. 16, 1920.

Application filed January 20, 1919. Serial No. 272,174.

To all whom it may concern:

Be it known that I, HILDING LÜBECK, a subject of the King of Sweden, residing at Herserud, Sweden, have invented certain

5 new and useful Improvements in Pneumatic Sleepers for Railroads, of which the following is a specification.

This invention relates to pneumatic sleepers for railroads, and has for its object to 10 provide a substitute for the wooden sleepers or ties generally used at present in railroad construction, which will be superior to the wooden sleepers not only as regards life, but also as regards elasticity.

15 In this connection the following factors must be taken into consideration: Not only is it necessary that such a substitute for wooden sleepers should counterbalance its probable higher initial cost by a longer life 20 and a consequent saving of labor for maintenance and renewal, but it should also have the same good qualities of wooden sleepers. As regards the initial cost, this is probably no longer of such importance, since the price 25 of wood and the cost of labor have gone up considerably and are likely to go still higher, so that the difference in initial cost between wooden sleepers and other sleepers will become smaller and smaller.

30 Various substitutes for wooden sleepers have been suggested in the past, some made of metal and some of concrete, but these did not present a satisfactory solution of the problem, partly because they presented unusual difficulties in laying and replacing, 35 but chiefly because they did not have the same elasticity as wooden sleepers. An elastic support of the rails is necessary, not only to minimize the short but exceedingly sharp blows brought about by the wheels passing over the rail joints, particularly at high speed, and to insure a smooth and pleasant running of the cars, but also to avoid unnecessary wear and tear on the rails and on 40 the rolling stock.

45 According to my invention, I provide pneumatic sleepers made of metal, preferably of sheet metal, which, as stated above, will be superior to wooden sleepers not only as regards durability, but as regards elasticity as well, and which can be easily laid, and also removed and replaced without difficulty. My pneumatic sleepers will also have the advantage that there is very little waste 50 in material, as compared with wooden sleepers; when after a long life they have done their service and have to be replaced, only

a small part of the material is actually lost, and the remainder can be remade into new sleepers or used for other purposes.

In the accompanying drawings, forming 60 part of this specification, I have shown one form of construction of my pneumatic sleeper, and two forms of its application. In these drawings, Figures 1, 2 and 3 illustrate one form of construction, Fig. 1 being 65 a central longitudinal section through one of my pneumatic sleepers, taken on line 1—1 of Fig. 2; Fig. 2 is a plan view of the sleeper; Fig. 3 is a cross section on line 3—3 of Fig. 2; Fig. 4 shows a modified form 70 of a safety support; and Fig. 5 shows in plan view another form of using my pneumatic sleeper.

The pneumatic sleeper shown in the drawings consists preferably of two dished sections, an upper section A and a lower section B made of metal, preferably of sheet metal; these two dished sections, when placed together with their edges in abutment, will form together a hollow sleeper 80 body. The two sections are preferably joined along their meeting edges C, as by welding or in any other suitable manner, so as to form an airtight body. This sleeper body is preferably filled with compressed 85 air or other gaseous medium under pressure, and for this purpose a valve D is suitably provided in the sleeper section A, secured to said section preferably by welding. After the air or other medium in the sleeper has 90 reached the desired pressure, the valve may be sealed by soldering, so as to prevent leakage.

The rails may be secured to the sleepers in any suitable way. As an example, I 95 have shown in the drawings metal bushings or blocks E secured to the upper sleeper section A as by welding, and extending into the interior of the sleeper body. These bushings have suitable screw-threaded sockets for the reception of the shanks of screws or bolts F, the heads of which engage the rail clamps G. A locking plate H is preferably interposed between the head of the screw F and the clamp G, this plate having 105 down-turned edges or flanges H' engaging the sides of the clamp G and up-turned flanges H'' adapted to engage two of the sides of the screw head, so as to lock the screw securely against accidental turning. 110

A protecting plate I is preferably interposed between the rail and the sleeper, so as

to prevent wear between these two parts, this plate having up-turned flanges I pressed down on the rail by the clamps G. If desired, the plate I may be made of insulating material, such as vulcanized rubber, hard fiber, etc.; so that the rails could be used as electrical conductors for telephone, telegraph or other electric signaling arrangement. As will be seen in Fig. 1, the bushings E extend to within a short distance of the lower sleeper section, and they will thus form at the same time a safety support to prevent material deformation of the sleeper in case a leak should occur which would release the pressure inside the sleeper. Of course a sufficient clearance must be left between the bushings E and the lower sleeper section, to allow for the pneumatic spring action when a train passes over the rail above the sleeper.

While in Figs. 1, 2 and 3 I have shown my pneumatic sleeper arranged crosswise of the rails, that is, at right angles to the direction of the rails, as is usual with wooden ties, I have illustrated in Fig. 4 a form in which the sleepers extend in the same direction as the rails. In this case oppositely-arranged sleepers are preferably connected by suitable cross bars or braces K.

It will be seen from the drawings that with the special form of sleepers and of rail-securing device shown, the placing of the sleepers in proper position and the removal of damaged sleepers and their replacement by new ones can be done without difficulty. I desire it to be clearly understood, however, that the drawings represent one example only of a sleeper constructed in accordance with my invention, and that various modifications may be made in the construction as well as in the application and use of the sleeper, without departing from the nature of my invention as set forth in the appended claims.

As stated above, any other suitable kind of securing means may be used to fasten the rails to the sleepers. In case such other securing devices do not include an inwardly-extending bushing, I may provide another safety support for the sleeper, such as for instance a block E' of metal or any other suitable material, located inside the sleeper, preferably in such a position that when the sleeper is used in track construction, such block will lie inside the sleeper underneath the rail (see Fig. 4), so as to prevent the sleeper from collapsing under the weight

of a passing train, in case the pressure inside the sleeper has been released accidentally or otherwise. This block may be secured to either one of the two sleeper sections, but it must of course be sufficiently spaced from the other section to allow for the pneumatic spring action of the sleeper.

I claim as my invention.

1. A pneumatic sleeper for railroads, comprising two sheet metal sections connected with each other directly along their edges, and so shaped as to inclose between them an air-tight space.

2. A sleeper for railroads formed by welding two dished metal sections together so as to inclose between them an airtight space.

3. A pneumatic sleeper for railroads, formed of two sheet metal sections pressed into substantially concave shape and rigidly connected along their edges, so as to inclose between them an airtight space.

4. A pneumatic sleeper for railroads, formed of two sheet metal sections directly welded together along their edges, one of said sections having a concave shape, so as to inclose with the other section an airtight space.

5. A pneumatic sleeper for railroads, comprising an upper and a lower metal section inclosing between them an airtight space, bushings secured to said upper section and extending within said space, but terminating at a distance from said lower section, said bushings having sockets open toward the outside to receive rail-securing means.

6. A sleeper for railroads, comprising an upper and a lower metal section joined along their edges, but otherwise spaced from each other, bushings secured to said upper section and extending within said space, but terminating at a distance from said lower section, said bushings having sockets open toward the outside to receive rail-securing means.

7. An elastic sleeper for railroads, comprising an upper and a lower section in contact with each other along their edges but capable of relative movement toward and from each other between said edges.

In testimony whereof I affix my signature in presence of two witnesses.

HILDING LÜBECK.
